CLAIM

We claim the ornamental design for a a display screen or portion thereof with graphical user interface, as shown and described.

DESCRIPTION

FIG. 1 is a front view of a first embodiment of a display screen or portion thereof with graphical user interface, showing the new design; and,

FIG. 2 is a second embodiment thereof.

The outer broken line showing the display screen or portion thereof and all other broken lines showing portions of the graphical user interface illustrate portions of the article of manufacture. None of the aforementioned broken line subject matters form part of the claimed design.

1 Claim, 2 Drawing Sheets

NICU		Pump Type: <i>LOCKPORT</i>	
Running 00000			
Ampicillin 100 mg/mL			
Dose 500.00 mg/kg	Reservoir Volume 12.00 mL	Rate 125.00 mL/h	
Concentration 120.25 mg/mL	Weight 68.00 kg	Infusion Duration 1:00:00 hr:min:sec	
	Secondary	Titrate	Bolus
			Clear TVD
